ABSTRACT

A fuel injection pumping apparatus for supplying fuel to an internal combustion engine includes an injection pump which supplies fuel through a passage controlled by a delivery valve. Fuel flowing past the delivery valve flows through a passage formed in a distributor member and which registers during a delivery stroke with an outlet. The return motion of the valve element of the delivery valve is achieved by means of a fluid spring which includes a plunger which is forced into a chamber during delivery of fuel by the injection pump. The fluid within the chamber is pressurised and when the delivery of fuel is complete the plunger bears against the valve element of the delivery valve to return the element to its original position.

7 Claims, 1 Drawing Figure

FLUID DELIVERY VALVE SPRING

This invention relates to liquid fuel pumping apparatus for supplying fuel to internal combustion engines and of the kind comprising in combination, an injection pump, a distributor member rotatable in a body part, the injection pump and distributor member being adapted to be driven in timed relationship with an associated engine, the distributor member including a passage communicating with the pumping chamber of the injection pump, and said passage registering in turn during successive delivery strokes of the injection pump, with outlet ports formed in the body part and which in use, communicate respectively with the injection nozzles of an associated engine, and a delivery valve in said passage, said delivery valve opening during the delivery of fuel by the injection pump.

The object of the invention is to provide such an apparatus in a simple and convenient form.

According to the invention, in an apparatus of the kind specified, said delivery valve comprises a valve element movable to an open position by the pressure of fuel developed by the injection pump, and a fluid spring against the force exerted by which the valve element moves to the open position, said fluid spring acting in part to effect movement of the valve element to its closed position.

According to a further feature of the invention, said fluid spring is charged with fuel during the delivery strokes of the injection pump, a non-return valve being provided to trap the fuel under pressure.

One example of a fuel pumping apparatus in accordance with the invention will now be described with reference to the accompanying drawing which shows a sectional side elevation of a portion of the apparatus.

Referring to the drawing, there is provided a body part 10 in which is mounted a rotary cylindrical distributor member 11. Also provided is an injection pump 12 and the injection pump and distributor member 11 are adapted to be driven in timed relationship with an engine with which the apparatus is associated. In practice, the injection pump comprises a pair of reciprocable pumping plungers which are accommodated within a transversely extending bore formed in the distributor member. Surrounding the distributor member is an annular cam ring on the internal peripheral surface of which is formed a plurality of pairs of inwardly extending cam lobes. Interposed between the internal surface of the cam ring and the plungers are rollers respectively which are mounted upon shoes. As the distributor member rotates, inward movement will be imparted to the plungers, such inward movement occurring during the delivery stroke of the injection pump.

The pumping chamber of the injection pump communicates with a passage 13 formed in the distributor member, and which communicates with a radially extending passage 14. The radially extending passage breaks out onto the periphery of the distributor member, and is positioned to register in turn, and during successive delivery strokes of the injection pump, with a plurality of outlet ports 15 formed in the body part. The outlet ports in use, are connected respectively to injection nozzles 16 of the associated engine.

The apparatus also includes a feed pump not shown which supplies fuel to the injection pump during the filling strokes thereof, the amount of fuel supplied to

the injection pump being controlled by throttling means not shown.

The apparatus also includes a delivery valve generally indicated at 16a and this includes a cylindrical valve element 17 which is slidably located within an enlargement 18 of the passage 13. The valve element 17 has a plurality of flats formed on its peripheral surface, and which extend to a tapered portion of the element. In the closed position of the delivery valve, the flats are not exposed beyond the end of the enlarged portion 18, but during delivery of fuel by the injection pump, the valve element is moved axially and the flats become exposed beyond the portion 18 thereby to permit fuel to flow from the passage 13 to the passage 14, and a passage 15 to the respective injection nozzle.

There is also provided a plunger 19 which bears against the valve element 17, the plunger 19 extends through a bore formed in a plug 20 and within which is defined a chamber 21. Mounted within the chamber 21 is a stop member 22, which is engageable by the plunger 19 to limit the extent of movement of the plunger and also the valve element 17.

The chamber 21 is in communication with the passage 14 by way of a non-return valve 23 which comprises a ball which can co-operate with a seating defined in a passage communicating with the chamber and extending substantially at right angles to the bore in which the plunger is mounted. The valve acts to prevent loss of pressure within the chamber 21 and the extent of movement of the ball away from the seating is determined by means of the plunger 19. In use, the chamber 21 becomes charged with fuel under pressure from the passage 14, this fuel being supplied by the injection pump. The pressure is retained within the chamber 21 by the valve 23, and this pressure acts upon the plunger to assist movement of the valve element 17 towards the closed position as is shown in the drawing. The chamber 21 and in particular the fuel pressure within it, together with the plunger 19 constitute a fluid spring which replaces the more conventional form of coiled compression spring which has been used hitherto and which is subject to limitations of design due to stress and frequency considerations.

It will be noted that the flats are only uncovered after a predetermined movement of the valve element 17, and during closure of the valve element relief of fuel under pressure in the passage 14 and the communicating outlet 15 together with the fuel in the pipe line interconnecting the outlet 15 with the injection nozzle 16, occurs. If desired, the outlets 15 may be provided with pressurising valves, the purpose of which is to minimise the risk of cavities forming within the outlets 15 and passage 14.

I claim:

1. A liquid fuel pumping apparatus comprising an injection pump, a distributor member rotatable in a body part, the injection pump and distributor member being driven in timed relationship, the distributor member including a passage communicating with the injection pump, and said passage registering in turn during successive delivery strokes of the injection pump, with outlet ports formed in the body part, and a delivery valve in said passage, said delivery valve opening during the delivery of fuel by the injection pump, said delivery valve comprising a valve element movable to an open position by the pressure of fuel developed by the injec-

tion pump, and a fluid spring against the force exerted by which the valve element moves to the open position, said fluid spring acting in part to effect movement of the valve element to its closed position.

2. An apparatus as claimed in claim 1 including passage means through which said fluid spring is charged with fuel during the delivery strokes of the injection pump, and a non-return valve in said passage means to trap the fuel under pressure.

3. An apparatus as claimed in claim 1 in which the fluid spring includes a plunger for engagement by the valve element, said plunger entering into a chamber containing fuel, and passage means through which the chamber is charged with fuel during a delivery stroke of the injection pump.

4. An apparatus as claimed in claim 3 including a non-return valve in said passage means operable to trap

fuel under pressure within said chamber.

5. An apparatus as claimed in claim 4 in which said chamber is defined within a plug which can be mounted in a recess defined in the distributor member, said plunger being located within a bore defined in said plug and communicating with said chamber.

6. An apparatus as claimed in claim 5 including a stop located in the chamber and acting to limit the extent of movement of the plunger and the valve element.

7. An apparatus as claimed in claim 6 in which the non-return valve comprises a ball located within the chamber the ball co-operating with a seating defined in a passage extending out of said chamber substantially at right angles to the bore, the plunger acting to limit the movement of the ball away from the seating.
